UNITED STATES PATENT OFFICE.

CHARLES J. BARRENPOHL, OF NEW YORK, N. Y.

LIFTING DEVICE.

1,216,541.

Specification of Letters Patent. Patented Feb. 20, 1917.

Application filed February 1, 1916. Serial N. 75,493.

To all whom it may concern:

Be it known that I, CHARLES J. BARRENPOHL, a citizen of the United States, residing at Tompkinsville, in the county of Richmond, Borough of Richmond, city and State of New York, have invented certain new and useful Improvements in Lifting Devices, of which the following, taken in connection with the accompanying drawings, is 10 a full, clear, and concise description.

The present invention relates generally to improvements in lifting devices and more particularly to lifting devices or jacks for vehicles and the like.

15 The principal object of the present invention is to provide a lifting device or jack, which will be particularly adaptable to the requirements of motor-driven vehicles, and may be permanently attached thereto, so as 20 to be instantly ready for use for raising the vehicle from its supporting surface, in order to effect adjustments and repairs thereto.

A further object of the present invention 25 is to provide a lifting device or jack, which will be simple in construction, and may be economically produced so as to possess great durability and which will be so designed that it may be attached to existing forms of 30 motor vehicles or the like, without alteration of the structure thereof or may be readily incorporated in vehicles, especially 35 designed to provide for the embodiment of my invention therein.

My invention is also designed to enable 40 one to simultaneously raise all four wheels of the vehicle from contact with the supporting surface with a minimum of effort and to obviate the many disadvantages incident to the employment of the ordinary 45 jacks of lifting devices now in use, means being incorporated in my invention to assure positive and efficient operation thereof and to safe-guard the user against injury by the accidental dropping or lowering of 50 the vehicle, while adjustments or repairs are being made, as frequently happens with known forms of jacks.

Other objects and advantages of the employment of my invention will become manifest as the description proceeds and I would have it understood that I reserve unto myself the full range of equivalents of structure and uses to which I am entitled under 55 my invention in its broadest aspect.

I shall now proceed to describe my invention with reference to the accompanying drawings and then point out with more particularity, the essential elements of novelty therein, in the appended claims.

In the drawings.

Figure 1 is a top plan view of a part of a chassis of a motor vehicle with my improved lifting device applied thereto.

Fig. 2 is a similar top plan view showing a modified construction.

Fig. 3 is a side elevation of a part of a chassis of the motor vehicle showing my invention in normal or folded position.

Fig. 4 is a similar view disclosing the relative position assumed by the parts of my invention when the motor-driven vehicle has been raised or lifted thereby.

Fig. 5 is an enlarged detail of one type of modification of the standards forming a part of my invention, showing the method of attaching the caster or roller.

Fig. 6 is an enlarged detail in section, taken on line 9—9 of Fig. 1, showing a connecting member, which I employ, and

Fig. 7 is an enlarged detail of a preferred form of ratchet controlling mechanism.

Referring now to the drawings in detail, in which like characters of reference are employed to designate similar parts throughout the several views, 7 represents the frame 85 of a motor vehicle, from which the forward and rear axles 3 and 9 are suspended on the customary springs 10 and 11, the axles carrying the wheels 12 and 13.

Preferably mounted intermediate of the forward and rear axles 12 and 13 and supported by the frame, in any suitable manner or as herein shown, by the brackets 14 and 15 fastened to the underside of the running board 16 is a screw 17. This screw is journaled in bearings formed in the brackets 14 and 15 and is provided with right and left-hand threads 18 and 19, as shown in Figs. 1 and 2.

Positioned up on the screw 17 and threaded to mesh therewith for actuation in opposite directions are guide blocks or members 20 and 21, to which are pivotally connected the rods 22 and 23. As an example of the type of pivotal connection, between the members 20 and 21 and the rods 22 and 23, the blocks or members may be provided with extending ears 20^a and 21^a, between

which an eye formed in each rod may be positioned and a pin passed therethrough. The other extremities of the rods or bars 22 and 23 are movably connected, such as shown in Fig. 6, to the socket members 24 and 25 supported by the transversely extending rods 26 and 27 carried by the standards 28 and 29. In the connection shown in Figs. 1 and 6 the rods or bars 22 and 23 are connected to the socket members 24 and 25 by means of connecting members 22^a and 23^a respectively. The connection of the bars 22 and 23 with the members 22^a and 23^a may be effected in any suitable manner, such as being firmly held by means of union members 22^b and 23^b. In the modification shown in Fig. 2, the bars 22 and 23 are connected directly to the socket members 24 and 25, which latter members in this instance are provided with two of the slots 24^a shown in Fig. 6 and function in a similar manner, as in the case where a single slot is provided which will hereinafter be more fully described. The standards 28 and 29 are mounted to rotate on the forward and rear axles 8 and 9 respectively, the means for effecting this being, for instance, an eye or collar 30 and 31 surrounding the respective axles adjacent to the inner side of the wheels and which are formed with sleeves or sockets 30^a and 31^a within which the upper extremities of the standards 28 and 29 may be welded, threaded or otherwise suitably secured.

The transversely extending stay-bars 26 and 27 may be fastened or rigidly secured to the standards 28 and 29 in any suitable manner, so as to firmly and immovably support the socket members 24 and 25, with which the push rods or bars 22 and 23 have a movable connection, as aforesaid. The enlarged detail in Fig. 6 illustrates one such form of movable connection, wherein the end of the rod 22 is formed with a reduced portion at its end providing a tongue 22^b, which is connected to the socket 24 and retained within said socket by an enlarged portion or ball 22^c, the tongue moving within the slot 24^a provided in said socket member 24.

As will be observed from the drawings, in order to afford the requisite rigidity to the standards 28 and 29 and to prevent their spreading under the stress of supporting the load, I preferably provide obliquely disposed stay-rods 32 and 33 connected to the socket members 24 and 25 and to the standards 28 and 29 in proximity to their lower ends. The stay rods 32 and 33, the socket member supporting rods 26 and 27, the standards 28 and 29, and the push rods 22 and 23 may be made of any suitable material and in the form of tubing, or T, or I-iron, the latter being particularly advantageous for the formation of the standards and the

parts directly connected thereto, as possessing a greater degree of resistance to torsional stress than tubing or T-iron.

From my invention so far described, it will be obvious that upon the rotation of the crank 34 in the direction of the arrow shown in Fig. 7, the block or guide members 20 and 21, preceded by the scrapers 48 and 49, attached thereto, clear the screw threads of foreign substances, and are caused to approach each other by the revolution of the screw 17, thus drawing the respective bars or rods 22 and 23 toward each other, this movement of the push rods will impart a gradual rotary movement to the respective lifting members, supported by the forward and rear axles, in opposite directions, so that upon the guide blocks 20 and 21 reaching the limit of their inward movement, the standards 28 and 29 will be perpendicular and will have raised the wheels of the vehicle out of contact with the supporting surface, as shown in Fig. 4. To facilitate the rotary movement of the lifting elements as just described, I have found it expedient to provide each standard at its lower extremity with a wheel or roller, such, for example, as shown in Fig. 5, wherein a caster 35 having a shank 36 seated in the base of the standard 37 is employed, a cotter pin 38 passing through the exposed portion of the shank of the caster to prevent accidental dislodgment thereof.

To permit the operator to have complete control over the actuation of the screws 17 and the interconnected parts, I have found it desirable to key a ratchet wheel 39 to one end of the screw 17, which may be provided with a squared shoulder for the purpose, a pawl 40 being positioned adjacent to this ratchet wheel and being normally held in contact therewith by the spring 41, this pawl preventing the unrestricted revolution of the screw in a direction opposite to that shown by the arrow in Fig. 7 during the lifting movement. To effect the lowering of the vehicle by gravity under control of the screw, and the return of the lifting elements to their normal position of rest therebeneath (as shown in Figs. 1, 2 and 3), the crank 34 may be moved a slight distance in the direction of the arrow to permit the dislodgment of the pawl 40 from the ratchet 39 by the manipulation of the eccentric 42, whereby the pawl is moved on its pivot 43, so that the spring 41 will engage the surface 44 thereof and hold it out of contact with the ratchet.

The brackets 14 and 15 may be fastened to the running boards by bolts, screws, or in any other suitable manner, or may be supported therebeneath on brackets or other means independently of the running boards, the ends of the screw 17 in any embodiment of my invention preferably terminating

within the vertical plane of the edge of the running boards, so that there are no projecting surfaces to detract from the appearance of the vehicle or interfere with its operation, the crank 34 being detachable from the screw, so that it may be carried in the tool box or other convenient part of the vehicle.

It will be manifest that in addition to the efficacy of my invention as a jack or lifting device in making roadside repairs or adjustments, it also is particularly advantageous as a substitute for turn-tables, such as are now employed in garage equipment. By the provision of swiveled rollers, such as illustrated in Fig. 5, when the vehicle has been jacked up, as shown in Fig. 4, it may be readily moved in any direction to facilitate storage, cleaning and the like. In the latter connection, if desired, the vehicle may be protected against unauthorized use by locking the pawl 40 in engagement with the ratchet 39 by means of a pad-lock, such as shown at 45, passing through eyes 46 and 47, as shown in Fig. 7. By this means, it will be evident that no one but the one possessing the key to the lock will be able to restore the lifting elements to their normal position beneath the car and make use of the vehicle.

There are many other avenues of use for my invention and it is obvious that there may be many changes made in structural details without departing from the spirit and scope of my invention, the application herein shown being simply employed for the purpose of furnishing a clear and comprehensive description.

Having thus described my invention what I claim as new herein and desire to secure by Letters Patent is:

1. A lifting device embodying lifting elements connected to the axles of a vehicle and means for imparting a rotary motion to said lifting elements to raise the vehicle from contact with its supporting surface, said means embodying a screw, a plurality of members actuated thereby to move in opposite directions transversely of the vehicle and means of connection between said elements and said members, said actuating means applying power to said elements in a direction longitudinally of the vehicle.

2. A lifting device comprising lifting elements supported from the axles of a vehicle and means for simultaneously moving all of said elements in a downward direction to raise the vehicle out of contact with the supporting surface and in the opposite direction to lower the vehicle to its position on the supporting surface and return said lifting elements to their normal position of rest, said means embodying a screw supported by said vehicle transversely thereof, a plurality of members actuated thereby and movable in opposite directions on said screw and means of connection between said members and said lifting elements, whereby upon the rotation of said screw, the movement of said members transversely of the vehicle will impart power to said connected means in a direction longitudinally of the vehicle to impart a rotary motion to said lifting elements.

CHARLES J. BARRENPOHL.
